DISPLAY PACKAGE FOR A HAND TOOL

Sandy Levin, Whitestone, Queens, N.Y., assignor to Pioneer Merchandise Corp., Flushing, N.Y., a corporation of New York

Filed June 28, 1965, Ser. No. 85,919

Term of patent 14 years

(Cl. D58—2)

FIG. 1

FIG. 2

FIG. 3

FIG. 4

The dominant features of my design reside in the portions shown in full lines.

I claim:

The ornamental design for a display package for a hand tool, as shown.
